[57] CLAIM

The ornamental design for a corner clock, as shown and described.

DESCRIPTION

FIG. 1 is a perspective view of top and front of a corner clock showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The numbers and hands shown in phantom lines are not part of the present design.
